UNITED STATES PATENT OFFICE

171,242

TOOLBOX

Gaston A. Belf and Arthur Lustig, New York, N. Y.

Application July 2, 1953, Serial No. 25,763

Term of patent 7 years

(Cl. D58—13)

To all whom it may concern:

Be it known that we, Gaston A. Belf, a citizen of the United States of America and resident of the city of New York, county of Queens, State of New York, and Arthur Lustig, a citizen of the United States of America and resident of the city of New York, county of Queens, State of New York, have invented a new, original, and ornamental Design for a Toolbox, of which the following is a specification, reference being had to the accompanying drawings, forming a part hereof.

In the drawings:

Figure 1 is a top perspective view of a toolbox, showing our new design;

Fig. 2 is a perspective exploded view, showing the cover portion removed from the bottom portion of the box;

Fig. 3 is a perspective view of the underside of the cover portion of the box;

Fig. 4 is a cross-sectional view thereof taken on the lines 4—4 of Fig. 1; and

Fig. 5 is a similar cross-sectional view, with the cover being in partly open position.

We claim:

The ornamental design for a toolbox, as shown.

GASTON A. BELF.

ARTHUR LUSTIG.
